METHOD FOR HEATING OIL

Application filed January 29, 1929. Serial No. 335,834.

This invention relates to an improved method and apparatus for cracking oil and has particular reference to that system of oil conversion wherein the oil undergoing treatment is decomposed while in the vapor phase and at temperatures generally in excess of 1000° F.

In the cracking of oil in the vapor phase it is customary to subject the oil first to temperatures sufficiently high to vaporize the oil but without substantially cracking the same. The oil which remains in liquid form after being thus initially heated is removed from the system while the vaporized fractions thereof are separately passed into a high temperature or converting zone wherein said oil vapors are brought to cracking temperatures and the conversion reactions are permitted to continue for a desired period of time. It has been found in the operation of these systems that the vapors entering the cracking or high temperature zone of the heating apparatus contain an appreciable amount of oil in liquid form, due, possibly, to entrainment. This liquid oil in the converting zone is highly undesirable for the reason that it collects on the highly heated walls of the tubes used in the cracking zone and produces a coke or carbon deposit which interferes seriously with heat transfer, blocks the free passage of oil vapors through the tubes and interferes in many other respects with the sustained or continued operation of commercial systems of this character.

It is therefore important to deprive oil vapors of all liquid entrainment before such vapors are admitted into the high temperature cracking tubes, and it is to this end that the present invention is specifically directed.

It is therefore an outstanding object of the invention to provide an oil heater for cracking oil in the vapor phase wherein the heater is formed to include a setting divided by a transverse bridge wall into burner and tube compartments, the tube compartment being provided with a series of tubes through which the oil vapors travel while being subjected to the decomposition temperatures prevailing in the heater and wherein the furnace gases after passing over said tubes, but

before leaving the setting and at relatively low temperatures, are brought into contact with a plurality of relatively enlarged tubes constituting what is known as a preheating or drying section, whereby the waste heat of the furnace is utilized for heating the oil and oil vapor passing through said preheating bank to vaporize the liquid content thereof before said vapors are admitted into the cracking tubes of the apparatus.

For a further understanding of the invention reference is to be had to the following description and to the accompanying drawing wherein:

Figure 1 is a diagrammatic view, partly in vertical section, of the apparatus employed in carrying out the present invention.

Figure 2 is a transverse sectional view on the line 2—2 of Figure 1.

Figure 3 is a view showing a slightly modified form.

Referring more particularly to the drawing, the numeral 1 designates an oil furnace or converter which is formed to comprise a setting 2 provided internally with a vertical transversely extending bridge wall 3, which divides the interior of the converter into burner and tube compartments 4 and 5 respectively. The burner compartment is provided with oil burners or other combustion devices 6 and these furnace gases pass upwardly toward the roof 7 of the converter and then sweep downwardly through the tube compartment 5, finding exit from the converter by way of the stack or other outlet 8.

Arranged within the converter are longitudinally extending rows or passes of cracking tubes 9. The upper pass, indicated by the characters 9a, pass over the burner compartment 4, rests on the top of the bridge wall 3 and also extends over the tube compartment 5. This pass of tubes has its forward end connected with a header 10, while the rear ends of the upper pass of tubes are connected by return bends, or other suitable means, with the lower pass of tubes 9, the converted vapors leaving the outlet ends of the tubes 9 being passed into cooling and fractionating apparatus 11.

Arranged in the tube compartment 5 below the tubes 9 is a bank of preheating or drying tubes 12. These tubes extend substantially at right angles to the tubes 9 and are 5 of materially greater diameter. For example, the tubes 9 may possess an outside diameter of three inches, whereas the tubes 12 possess, for example, an outside diameter of six inches or more. The tubes 12 are located in the 10 relatively cooler portions of the converter. Thus the temperature in the burner compartment may be as high as 2200° F., the temperature in the upper portion of the tube compartment 1800° F., the temperature 15 around the preheating tubes 12 1300° F., and the outlet temperature substantially 1200° F.

In carrying out the system oil is first passed 20 through a tube still or vaporizer 13 where it is brought to a temperature of approximately 700° F. This temperature is sufficiently high to vaporize the desirable fractions of the oil but not to materially crack the same. The oil leaves the vaporizer 13 and passes into 25 an evaporator 14, which serves to separate the vaporized fractions of the oil from the liquid fractions, the latter being discharged from the bottom of the evaporator as fuel oil. From the evaporator the vapors pass by way 30 of a pipe line 15, in which is arranged a liquid trap 16 to the inlet side of the preheating tubes 12, and enter said tubes at a temperature of, roughly, 600° F. The vapors are then passed through the tubes 12 and subjected to the temperatures prevailing in the 35 outlet side of the converter. Due to the relatively large diameter of the tubes comprising the bank 12 and the fact that these tubes are located in the outlet portion of the converter, the oil vapors passing through the tubes 12 40 are dried or preheated to remove therefrom all liquid entrainment, with the result that when said vapors are discharged from the tubes 12 and pass by way of a pipe line 17 to the header 10 they are in a substantially 45 dry state when introduced into the inlet pass of the tubes 9. By reason of their relatively large internal area the tubes 12 may be readily cleaned from time to time of such carbon or coke deposit which may accumulate there- 50 in. The tubes comprising the bank 12 are preferably connected so that the vapors pass therethrough serially, since this tends to produce high velocity and good heat transfer. The temperature rise in the vapors while 55 passing through the drying tubes varies from 80 to 100 degrees, and this temperature is sufficient to thoroughly dry the vapors but not sufficiently high to overheat or appreciably crack the same. For example, the outlet 60 temperature of the vapors when leaving the tubes 12 may be approximately 700° F.

In the present invention the coke which forms as a result of the drying will not choke the tubes that are arranged in parallel order, 65 which is the arrangement in the bank 9. The

presence of coke, for example, in the entrance portion of the tubes 9a is extremely detrimental due to the very high temperatures at the inlet and which if present is apt to result in the burning out and mechanical 70 failure of the tubes. Coke on the interior of the preheater or drier 12, will not in any way be damaging since the furnace temperature at this point is in the neighborhood of 1200° F. The tubes 12 can, therefore, 75 operate with small amounts of coke in them for a period of time without danger of burning out because of the low temperatures employed. One of the outstanding features of 80 this invention is that of introducing dry or slightly super-heated oil vapors into a cracking zone or tube.

We prefer for reasons of economy to situate the preheating or drying tubes in the converter setting. It is obviously within the 85 scope of the invention, however, to place these tubes in a separately heated element, as disclosed in Figure 3, the element being indicated by the numeral 18 and is arranged as a part of the pipe line leading from the 90 evaporator 14 to the tubes 9.

What is claimed is:

1. The method of cracking oil in the vapor phase, which consists in heating a continuously moving elongated stream of oil of restricted cross-sectional area to a temperature at which portions thereof will vaporize without molecular decomposition, passing the heated oil to an enlarged zone and therein separating said vaporized product from the 95 portions which do not vaporize without molecular decomposition, then passing said vapors through an intermediate heating zone in an elongated stream of restricted cross-sectional area whereby the temperature of the vapors is raised sufficiently to bring the vapors to a substantially dry gaseous condition without appreciable cracking thereof, and finally passing said dry vapors in an elongated stream of restricted cross-sectional 100 area materially less than that of the intermediate zone to raise the temperature of the dry vapors to a cracking temperature in excess of substantially 1000° F.

2. The method of cracking the hydrocarbon oil in the vapor phase, which consists in passing a moving stream of such oil through a primary heating zone and therein heating the oil to a temperature at which portions thereof will vaporize without molecular decomposition, substantially separating such vapors in an externally unheated zone from the remaining portions of the oil which do not vaporize without molecular decomposition, passing said vapors in a confined moving stream through an intermediate heating zone possessing a higher temperature than said primary zone to effect vaporization of the entrained unvaporized oil present in said vapors as a mist or suspensoid to reduce said 115 120 125 130

- vapors to a substantially dry moisture-free state without permitting any appreciable cracking thereof to take place, then passing said dry vapors in a confined moving stream 5 at a velocity materially greater than the velocity of the vapors in the intermediate zone through an elongated cracking zone of restricted cross-sectional area wherein said vapors attain a cracking temperature in excess 10 of 1000° F., and utilizing the same products of combustion which are employed to heat the cracking zone to a high temperature for heating the intermediate drying zone to a lower temperature.
- 15 3. The method of cracking hydrocarbon oil in the vapor phase, which consists in passing a moving stream of such oil through a primary heating zone and therein heating the oil to a temperature at which portions thereof 20 will vaporize without molecular decomposition, substantially separating such vapors while removed from heat application from the remaining portions of the oil which do not vaporize without molecular decomposi- 25 tion, passing said vapors in a confined moving stream through an intermediate heating zone possessing a higher temperature than said primary zone to effect the vaporization of the entrained unvaporized oil present in said vapors as a mist or suspensoid whereby 30 said vapors are reduced to a substantially dry moisture free state without appreciable cracking thereof taking place, and then passing said dry vapor in a confined moving stream at a velocity materially greater than 35 the velocity of the vapors in the intermediate zone through an elongated cracking zone of restricted cross-sectional area wherein said vapors attain a cracking temperature in ex- 40 cess of 1000° F.
4. The method of cracking hydrocarbon oil into vapor phase, which consists in passing a moving stream of such oil through a primary heating zone and therein heating the oil to a 45 temperature at which portions thereof will vaporize without molecular decomposition, substantially separating such vapors in an externally unheated separating zone from the remaining portions of the oil which do not va- 50 porize without molecular decomposition, passing said vapors in a confined moving stream through an intermediate heating zone possessing a higher temperature than said primary zone to effect the vaporization of en- 55 trained unvaporized oil present in said vapors without any appreciable cracking of the vapors taking place, then directly passing said dry vapor from the intermediate heating zone and without reduction in its total weight 60 through an elongated conversion zone of re- 65 stricted cross-sectional area, wherein said vapors attain a conversion temperature in ex- 70 cess of 1000° F., and causing the vapors to travel at a materially greater velocity 75 through said conversion zone than the ve- 80 locity of travel thereof through the intermediate drying zone by varying the cross sectional area of the said intermediate drying zone and the conversion-zone.
5. The method of cracking hydrocarbon oil 85 into vapor phase, which consists in passing a moving stream of such oil through a primary heating zone and therein heating the oil to a temperature at which portions thereof will vaporize without molecular decomposition, 90 substantially separating such vapors from the remaining portions of the oil which do not vaporize without molecular decomposition, passing said vapors in a confined moving stream through an intermediate heating zone 95 possessing a higher temperature than said primary zone to effect the vaporization of en- 100 trained unvaporized oil present in said vapors without any appreciable cracking of the vapors taking place, then directly passing said dry vapor from the intermediate heating zone and without reduction in its total weight through an elongated conversion zone of re- 105 stricted cross-sectional area, wherein said vapors attain a conversion temperature in ex- 110 cess of 1000° F., causing the vapors to travel at a materially greater velocity through said conversion zone than the velocity of travel thereof through the intermediate drying zone, and utilizing the same products of com- 115 bustion which are employed to heat the conversion zone to a high temperature for heating the intermediate drying zone to a lower temperature.
